UNITED STATES PATENT OFFICE.

WALTER L. REIN AND CHARLES G. REIN, OF CHICAGO, ILLINOIS.

POLISHING BRUSH.

Application filed January 23, 1928. Serial No. 248,808.

Our invention relates to polishing brushes, and more particularly to such brushes as are power-operated, and it is our main object to provide a brush of this kind which is easily removable from the power element after it has become clogged.

A further object of the invention is to provide a peculiar construction whereby the elements of the novel brush may easily come apart for the cleaning thereof.

A still further object of the invention is to construct the base or holder of the novel brush on novel lines, whereby to avoid difficulty in mounting or removing the holder from the power element.

A final, but nevertheless important object of the invention is to design the novel brush on lines of utmost simplicity, in order that the same may be easily handled and inexpensively produced.

With the above objects in view and any others that may suggest themselves from the specification and claims to follow, a better understanding of the invention may be gained by reference to the accompanying drawing, in which—

Figure 1 is a longitudinal section through the brush;

Fig. 2 is a perspective view of its holder; and

Fig. 3 is an end view of the brush taken from the left-hand side of Figure 1.

Polishing brushes of the type we have in mind are usually fitted upon the shaft or spindle of a portable power device, such as an electric drill, motor or the like. In the usual practice, the operative end of the power shaft is suitably formed to receive the brush, and the latter is then firmly secured to the shaft by nuts, washers, and other means conducive to fixing the brush both tightly and non-rotatably relative to the shaft or spindle. This method of mounting the brush has two serious disadvantages, namely, 1: that the sections of the brush, which are disks of soft cloth, are so tightly packed that they lose their gentle and flexible value as against the surface to be polished, and 2: that considerable difficulty is had in removing the brush after it has become clogged with the cleaning compound, such as wax or similar substance having a sticky or semi-solid consistency when in the form of a residue or coating on the brush sections. It has therefore been our intention to elimi-

nate these deficiencies and carry out the above mentioned objects to their fullest extent.

Referring specifically to the drawing, 5 denotes the operative end of the shaft or spindle projecting from a power device of the type previously mentioned. Our invention requires no changes whatever in the power device, but necessitates the cutting of the end of the shaft with a diametrically-directed slot 6 and the perforating of the same at an intermediate point with a cross bore 7, these being the only changes required.

The holder for the novel brush comprises mainly an arch-shaped wire 8 of medium gauge, such as No. 10 B & S wire, the cross bar 8^a of the arch seating in the slot 6. The legs of the arch extend parallel to the shaft 5 on opposite sides, and pass through perforations 9 in a disk 10 mounted loosely on the shaft through the agency of a medial aperture 11. The disk is positioned just back of the cross bore 7, and is checked from motion in a forward direction by the insertion of a cotter or other pin 12 through the said cross bore. The legs of the arch 8 emerge from the back side of the disk in the form of terminal transverse bends 13. The brush 14 consists of a mass of soft cloth disks, preferably of circular contour, the disks being centrally apertured to be strung on the shaft 5. As noted in Figure 1, the disks are also perforated on opposite sides of their central aperture to be strung on the legs 8 of the arch 8 to assume the position shown.

The frontal portion of the brush is gathered as indicated at 15 and the outermost sections sewed closed as indicated at 15^a or otherwise gathered permanently so as to fully enclose and jacket the end of the shaft. Since the brush has a rapid rotary motion and is applied to surfaces requiring a high polish, the gathered portions 15 of the brush will shield such surfaces from contact by any metallic portion of the brush, thus protecting the surfaces from becoming marred or otherwise injured.

In making up the brush, the arch 8 is provided with the ends 13 unbent, so that the sections of the brush 14 may be strung upon the arch and gathered as indicated at 15. The ends 13 are then bent outside the disk 10 to retain the same upon the legs of the arch. The shaft 5 is then inserted through the disk 10 and advanced until its slot 6 re-

ceives the cross bar 8^a of the arch. The soft mass of brush sections is now contracted toward the outer end of the structure to momentarily expose the cross bore 7, so that 5 the pin 12 may be inserted and spread to become locked to the shaft. It will now be seen that the metallic holder of the brush comprises a substantially rigid frame which is non-rotatably fixed upon the shaft, yet 10 easily slid off the same in a forward direction by the simple removal of the pin 12. This removal may be effected by again compressing the brush in an outward direction to expose the pin. 15 In the use of the brush, the fact that its every section is anchored to the frame-like arch 8 causes the brush to fully operate in connection with the shaft. Thus, no element of the brush can slip by reason of lost motion or an insecure fastening. Yet, the brush retains its free semi-loose consistency, so that 20 its action upon the surface polished is soft and gentle. In the event that the brush has become clogged with solid and soiled remnants or residue of the cleaning compound, it may be easily removed from the shaft by 25 the simple expedient just mentioned, and a brush on another holder applied to the shaft, so that the work of cleaning is but momentarily interrupted. The discarded brush is 30 cast aside until it is ready to be cleaned, at which time it may be easily removed from the arch by the unbending of the ends 13 of the arch legs, in which event the body of sections may easily be run off the arch legs. 35 In case the arch becomes deformed during the brush removing process, it may be discarded without any appreciable loss, since it is but a length of ordinary iron wire, which is trifling in cost. It is customary to boil a brush 40 of this kind in water or a suitable solution to loosen the cleaning compound deposits from it; and this may be done by immersing the brush even while on the wire holder, since 45 the brush sections are sufficiently loose on the latter to be reached and cleaned by the boiling water or solution.

In conclusion, it will be evident that we 50 have provided a brush which supplies to the power feature the advantages of the soft polishing cloth ordinarily used by hand. The novel brush is both in the proper condition for the work required of it and in fixed relation to the power element, so that no annoyance is experienced by the operator during 55 its use.

While we have illustrated and described our invention in the preferred form, it will be evident that the same is capable of many

minor changes and refinements, and it is our 60 intention to claim such changes and refinements as coming within the spirit and scope of the appended claims.

We claim:—

1. A power brush comprising a shaft 65 formed with a terminal recess, an arch with its cap seated in the recess and legs in spaced relation alongside the shaft, and a brush body impaled on the shaft and arch legs.

2. A power brush comprising a shaft 70 formed with a terminal recess, an arch with its cap seated in the recess and legs in spaced relation alongside the shaft, and a laminated brush body impaled on the shaft and arch 75 legs, the laminations opposite the said cap being gathered and fastened to embed said cap and the terminal portion of the shaft.

3. A power brush comprising a shaft having a perforation at an intermediate point, an arch non-rotatably applied at the forward 80 end of the shaft and having its legs extending alongside the shaft from said end, a plate mounted on the shaft back of said perforation, the plate being perforated to receive said legs, a stop for the plate secured in said 85 perforation, bends formed from said legs on the back of said plate, and a brush body mounted on the shaft and the legs between the plate and said end.

4. A power brush comprising a shaft 90 perforated at an intermediate point, an arch non-rotatably applied at the forward end of the shaft and having its legs extending alongside the shaft from said end, a plate mounted 95 on the shaft back of said perforation, the plate being apertured to receive said legs, a stop pin for the plate secured in said perforation, bends formed from said legs on the back of said plate, and a brush body mounted on the shaft and the legs between the plate and 100 said end.

5. A power brush comprising a shaft nicked in the forward end and perforated at an intermediate point, an arch-rod seated with its cap in said nick and having its legs extending in parallelism alongside the shaft from said end, a plate mounted on the shaft back of said perforation, the plate being apertured to receive said legs, a stop pin for the plate secured in said perforation, bends formed from 105 said legs on the back of said plate, and a brush body mounted on the shaft and the legs between the plate and said end.

In testimony whereof we affix our signatures.
